SIGNAL

Robert M. Cremer, Chicago, Ill.

Application March 19, 1934, Serial No. 716,387

7 Claims. (Cl. 200—83)

My invention relates to motor vehicle accessories and more specifically to arrangements for detecting abnormal conditions requiring attention by the operator, before such conditions become sufficiently serious to cause damage or inconvenience. It includes among its objects and advantages the elimination of unnecessary, irrelevant, or confusing signals or warnings; and, in connection with an oil sensitive signal, a minimum of parts combined with extremely simple adjustment means readily accessible to and understandable by an unskilled operator.

In the accompanying drawing:

Figure 1 is a section of a current-controlling device sensitive to hydraulic pressure;

Figure 2 is a wiring diagram; and

Figure 3 is a section as on line 3—3 of Figure 2.

In the embodiment of the invention selected for illustration, the mechanical terminal 10 is adapted to be connected with the high pressure portion of a lubricating system for the engine. The cup 12 is mounted on the terminal 10 by riveting as at 14. The cover 16 is in the form of an inverted cup, but is much shallower than the cup 12, so that its conical portion lies close to the diaphragm 18 and prevents injury to the diaphragm by high oil pressure. The two cups are united by an annular bead 20 formed as an integral part of the rim of the cup 12, with a washer 22 between the diaphragm and the lower cup. Crimping home this bead in a press of suitable power gives a satisfactory and durable oil tight joint. I have illustrated the edge of the diaphragm 18 also turned over the edge of the upper cup 16, as at 23. The cover 16 includes the cylindrical neck 24 housing the spring 26 and the combined mechanical thrust terminal and electrical grounding terminal 28.

The terminal 28 is in the form of an upwardly opening cup receiving the lower end of the spring 26, and its upper edge is flared at 30 to provide a flange for making contact with the electrical terminal 32. The support for the electrical terminal comprises the usual insulators 34 and 36 clamped between the flange 38 and the nut 40.

The cap 42 is threaded inside the neck 24 as at 44, and held in adjusted position against rotation by a resilient finger 46 riveted to the neck at 48 and engaging knurled teeth 50 on the cap.

The lower terminal 52 is supported similarly to the upper terminal 32, except that it is held against rotation about its horizontal axis. The flange 54 bears against the usual necked insulator 56, but the flat insulator 58 has its central opening in the shape of a circle with a sector

cut away, and fits the stem 60, which is similarly mutilated. The upper edge of the insulator 58 also has a sector cut away to leave a flat at 62 that abuts under the flange 20. The nut 64 clamps the insulators in place and the nut 66 clamps the lead-in wire 68 and also functions as a lock nut. The inner end of the contact 52 is formed into an upwardly directed point 53 to make electric contact with a button 55 mounted on the diaphragm.

Referring now to Figure 2, I have indicated the usual generator 70 electrically grounded at 72 and having the usual cut-out switch 74 for disconnecting the armature winding from the wiring carrying the battery potential when the ignition switch is turned on, until the generator is running and has built up sufficient voltage so that the battery will not discharge through the generator.

I have indicated a wire 76 running to the ignition switch, or other wiring energized by turning on the ignition switch; and the electrical terminal 78, disconnected from the wire 76 except when the generator is running and the cut-out switch 74 closes. From the terminal 78 I run wiring in series through a tell-tale light 80, and the lower contact 52 of the device of Figure 1. In the diagram illustrated the light 80 is between the device and the generator, and the device itself is electrically grounded by the mechanical terminal 10.

It will be obvious that the same generator terminal 78 may be connected to more than one instrumentality for detecting an abnormal condition. I have indicated another wire 82 connected to a second tell-tale light 84, and wires 86 and 88 connecting the tell-tale light to ground through a second instrumentality 90 which may be a gasoline gauge arranged to connect the wires 86 and 88 when the gasoline tank is almost empty, a thermostat for connecting said wires when the temperature of the cooling water becomes excessive, or any other detecting means designed to respond to an abnormal condition calling for attention by the operator.

The upper terminal 32 of the pressure sensitive device is similarly utilized, being connected in series with a third tell-tale light 92. This is a relatively very dim green light, which will light up when the engine is started, and burn continuously as long as the generator delivers voltage. Thus its failure to light when the engine is started warns the operator not only that the generator is not functioning and the ignition is being supplied by the battery, but that his

regular oil pressure gauge is his only reliance to keep track of oiling conditions until the generator is fixed.

In Figure 3 I have indicated the usual generator construction involving the grounded body 94, the grounded armature brush 96, and the brush 98 for delivering power through the cut out switch 74 to the battery wire 16. The wire 102, from which all the tell-tale lights 80, 84, and 92 are fed, is connected to the binding post 78 which is directly connected through the wire 104 to the brush 98. This gives the tell-tale system, as well as the battery, the benefit of the voltage adjustment of the third brush 106 from which a variable voltage is delivered to the field windings 108 to compensate for variations in speed of the engine and secure relatively constant voltage for the brush 98.

Without further elaboration the foregoing will so fully explain my invention that others may, by applying knowledge current at the time of application, readily adapt the same for use under various conditions of service.

I claim:

1. In a pressure detector; a housing comprising two opposed one-piece sheet metal cups united into an integral unit by bending the edge of one cup around the edge of the other cup; a diaphragm and an annular sealing washer clamped between the edges of said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; contact making and breaking means actuated by the diaphragm; and adjustable resilient means housed in said neck and opposing the yielding of said diaphragm in response to pressure; said resilient means comprising a cap threaded into the end of said neck, a helical spring carried by said cap, and a mechanical terminal carried on the inner end of said spring and bearing against said diaphragm; and an insulated electric terminal extending laterally from one side into the cup on the high pressure side of the diaphragm to underlie said contact making and breaking means.

2. In a pressure detector; a housing comprising two opposed one-piece sheet metal cups united into an integral unit by bending the edge of one cup around the edge of the other cup; a diaphragm and an annular sealing washer clamped between the edges of said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; contact making and breaking means actuated by the diaphragm and housed in said neck; and adjustable resilient means housed in said neck and opposing the yielding of said diaphragm in response to pressure; said resilient means comprising a cap threaded into the end of said neck, a helical spring carried by said cap, and a cup-shaped terminal carried on the inner end of said spring and bearing against said diaphragm; said contact means comprising a flared flange on the upper edge of said terminal, and an insulated terminal extending laterally into said neck from one side to overlie said flange.

3. In a pressure detector; a housing comprising two opposed one-piece sheet metal cups united into an integral unit by bending the edge of one cup around the edge of the other cup; a diaphragm clamped between the edges of said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; adjustable resilient means housed in said neck and opposing the yielding of said diaphragm in response to pressure; said resilient means comprising a cap threaded into the end of said neck, a helical spring carried by said cap, and a terminal carried on the inner end of said spring and bearing against said diaphragm.

4. In a pressure detector; a housing comprising two opposed one-piece sheet metal cups united into an integral unit by bending the edge of one cup around the edge of the other cup; a diaphragm between said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; and adjustable resilient means housed in said neck and opposing the yielding of said diaphragm in response to pressure; said resilient means comprising a cap threaded into the end of said neck, a helical spring carried by said cap, and a terminal carried on the inner end of said spring and bearing against said diaphragm.

5. In a pressure detector; a housing comprising opposed one piece sheet metal cups united into an integral unit by bending the edge of one cup around the edge of the other cup; a diaphragm clamped between the edges of said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; adjustable resilient means housed in said neck and opposing the yielding of said diaphragm in response to pressure; said resilient means comprising an abutment having threaded engagement with the end of said neck, and a helical spring pressed toward said diaphragm by said abutment; and an insulated electric terminal extending laterally from one side into the cup on the high pressure side of the diaphragm to underlie said contact making and breaking means.

6. In a pressure detector; a housing comprising opposed one piece sheet metal cups united into an integral unit by bending the edge of one cup around the edge of the other cup; a diaphragm clamped between the edges of said cups; the cup on the low pressure side of the diaphragm being relatively shallow and having wall portions lying close to the undistorted position of said diaphragm, to engage the diaphragm after a predetermined displacement thereof and protect it from further distortion; the cup on the low pressure side having a central neck; adjustable resilient means housed in said neck and opposing the yielding of said diaphragm in response to pressure; said resilient means comprising an abutment having threaded engagement with the end of said neck, and a helical spring pressed toward said diaphragm by said abutment; and an insulated electric terminal extending laterally from one side into the cup on the high pressure side of the diaphragm to underlie said contact making and breaking means.

abutment having threaded engagement with the end of said neck, and a helical spring pressed toward said diaphragm by said abutment; and an insulated electric terminal on the high pressure side of the diaphragm to underlie said contact making and breaking means.

7. In a pressure detector: a housing comprising opposed one piece sheet metal cups united into an integral unit by bending the edge of one 10 cup around the edge of the other cup; a diaphragm clamped between the edges of said cups; the cup on the low pressure side of the diaphragm being relatively shallow and having wall portions

lying close to the undistorted position of said diaphragm, to engage the diaphragm after a predetermined displacement thereof and protect it from further distortion; the cup on the low pressure side having a central neck; adjustable resilient means housed in said neck and opposing the yielding of said diaphragm in response to pressure; and an insulated electric terminal extending laterally from one side into the cup on the high pressure side of the diaphragm to underlie 10 said contact making and breaking means.

ROBERT M. CREMER.
